UNITED STATES PATENT OFFICE.

JAMES W. GLADSTONE, OF WEST ORANGE, NEW JERSEY.

BATTERY.

SPECIFICATION forming part of Letters Patent No. 742,857, dated November 3, 1903.

Application filed September 17, 1903. Serial No. 173,546. (No model.)

To all whom it may concern:

Be it known that I, JAMES W. GLADSTONE, a subject of the King of Great Britain, and a resident of West Orange, in the State of New

5 Jersey, have invented certain new and useful Improvements in Batteries, of which the following is a specification accompanied by drawings.

This invention relates to batteries, but 10 more particularly to primary batteries; and its objects are to improve upon the construction of such batteries, secure simplicity and compactness, and increase the internal conductivity.

15 Another object of the invention is to improve upon the construction of the sustaining-frame and clamping devices carried thereby for one of the electrodes.

Further objects of the invention will here- 20 inafter appear.

To these ends the invention consists of a battery for carrying out the above objects embodying the features of construction, combinations of elements, and arrangement of 25 parts, having the general mode of operation substantially as hereinafter fully described and claimed in this specification and shown in the accompanying drawings, in which—

Figure 1 is a side elevation, partly in section, of a battery embodying the invention. Fig. 2 is a vertical sectional detail view of the clamps. Fig. 3 is an enlarged sectional detail view of the means for locking the clamps. Fig. 4 is a view similar to Fig. 3, 35 but with the locking device in a different position; and Fig. 5 is an enlarged detail perspective view of the eccentric locking device.

Referring to the drawings, A represents a suitable container or vessel for the battery, 40 provided with the cover B of any suitable material, as porcelain. As shown, a rubber ring C encircles the cover for cushioning the same within the container. The negative plate D may be of copper oxid properly 45 molded, and it is supported from the cover B within the vessel by a supporting-frame or hanger, shown in this instance substantially U-shaped and consisting of the side bars E and cross-bar F. The hanger may be of plain 50 copper wire of a suitable gage bent into the desired shape and in this instance provided with screw-threaded ends G, affording pro-

vision for supporting the hanger from the cover by means of the nuts H. Binding-screws are provided for attaching the connecting-wires.

55 The hanger is provided with depending spring-clamps J and K, formed, preferably, of perforated metal, while means are provided for locking the free ends of the clamps together. The clamps J and K, as shown, are bent around the cross-bar F of the hanger and secured by rivets L. The free ends of the clamps, as shown, are bent inwardly and overlap and are provided with registering 60 apertures through which the eccentric locking device O is passed. The locking device O comprises a cylindrical key or stud provided with a cut-away portion P and a head Q. A removable pin R passes through the device 65 O for affording provision for manipulating the machine with the fingers. The clamps J and K have sufficient spring action to normally force them apart, as shown in Figs. 2 and 3. In these figures the clamps are separated to the fullest extent permitted by the locking device, because the cut-away or eccentric portion P of the key is in such position that the inwardly-bent portion of the clamp K is permitted to enter said cut-away 70 portion. By turning the key to the position shown in Fig. 4 the wide portion of the key enters the aperture in the inwardly-bent free end of the clamp K and forces the two clamps closer together, thereby tightly clamping the 75 electrode D between the same. Any desired number of the spring-clamps may be used, I having shown but two for convenience of illustration. I am also not to be understood as limiting myself to the particular form of 80 eccentric locking device shown, but have illustrated the preferred form of the invention.

85 The positive zinc plates S are arranged at each side of the negative plate D and are preferably cast into a U-shaped casting suitably supported from the cover B by means of the screw-threaded bolt or rod T, having the nut U and binding-screw V.

90 Obviously some features of this invention may be used without others, and the invention 95 may be embodied in widely-varying forms.

100 Therefore without limiting the invention to the construction shown and described nor

enumerating equivalents, I claim and desire to obtain by Letters Patent the following:

1. In a battery, the combination with an electrode and a supporting-frame or hanger, of a plurality of spring-clamps depending from said hanger, and means for locking the free ends of said clamps together, for substantially the purposes set forth.
2. In a battery, the combination with an electrode and a supporting-frame or hanger, of a plurality of spring-clamps depending from said hanger, the free ends of said clamps having perforations adapted to substantially register, and a locking device co-operating with said perforations affording provision for loosening and tightening the clamps, for substantially the purposes set forth.
3. In a battery, the combination with an electrode and a supporting-frame or hanger, of a plurality of spring-clamps depending

from said hanger, the free ends of said clamps being provided with a locking device affording provision for loosening and tightening the clamps, for substantially the purposes set forth.

4. In a battery, the combination with an electrode, and a supporting-frame or hanger, of a plurality of spring-clamps depending from said hanger, the free ends of said clamps being provided with an eccentric key or locking device for loosening and tightening the clamps, for substantially the purposes set forth.

In testimony whereof I have signed this specification in the presence of two subscribing witnesses.

JAMES W. GLADSTONE.
